UNITED STATES PATENT OFFICE

GEORGE M. LONG, OF BOSTON, MASSACHUSETTS, ASSIGNOR TO WARREN TELECHRON
COMPANY, A CORPORATION OF MAINE

DESIGN FOR A CLOCK CASE

Application filed June 12, 1931. Serial No. 40,172. Term of patent 14 years.

To all whom it may concern:

Be it known that I, GEORGE M. LONG, a citizen of the United States, residing at Boston, county of Suffolk, State of Massachusetts,

have invented a new, original, and ornamental Design for a Clock Case of which the following is a specification, reference being had to the accompanying drawings, forming

a part thereof. Fig. 1 of the drawings is a front view and Fig. 2 is a side view of a clock case showing my new design.

I claim:

The ornamental design for a clock case as

GEORGE M. LONG
